MICROMETER LOCK

Harry Kerslake, Pomona, Fla.

Application October 16, 1945, Serial No. 622,541

2 Claims. (Cl. 33—167)

1

This invention relates to micrometers, and more particularly to locking means for micrometers.

A main object of the invention is to provide a novel and improved locking structure adapted to be readily mounted on a micrometer of the conventional type for holding the micrometer locked in position when it is desired to obtain a reading thereon.

A further object of the invention is to provide an improved locking device of very simple structure which may be readily attached to a standard micrometer and which is adapted to lock the micrometer parts in fixed relation subsequent to making a measurement therewith so that the reading of the micrometer will not be disturbed by handling of the instrument.

Further objects and advantages of the invention will appear from the following description and claims, and from the accompanying drawings, wherein:

Figure 1 is an elevational view of a conventional micrometer of the type employed to measure outside dimensions of objects, said micrometer having mounted thereon a locking device according to this invention.

Figure 2 is an elevational view of a conventional micrometer of the type employed to measure inside dimensions of objects, said micrometer being equipped with a locking device in accordance with this invention.

Figure 3 is a top plan view of the top clamping element of the locking device of Figures 1 and 2.

Figure 4 is a bottom plan view of a lower clamp element employed with the locking device of this invention.

Referring to Figure 1, 11 designates a conventional micrometer of the outside dimension measuring type comprising a frame portion 12, a gauge sleeve 13 and a rotatable barrel 14, said rotatable barrel having an upper knurled portion 15. Frame 12 is formed with a rounded end portion 16. For at times securing barrel 14 in fixed relation to frame 12 a clamping device 17 is provided comprising a bottom clamping member 18 adapted to engage rounded portion 16 and to be locked thereto by a bolt 19. Clamping member 18 is formed with an eye portion 20 in which is rigidly secured an upwardly projecting rod 21. Slidably engaged with rod 21 is a sleeve 22 to the upper end portion of which is rigidly secured a clamping member 23 adapted to engage knurled portion 15, said clamping member 23 being formed with an eye portion 24 in which the sleeve 22 is secured, and with a pair of lug portions 25, 25 through which passes a bolt 26 having threaded thereon a

2

wing nut 27 for adjusting the clamping pressure of clamping member 23 with respect to knurled portion 15.

When a measurement is to be made, wing nut 27 is loosened sufficiently to permit rotation of barrel 14 with respect to frame 12 but not enough to allow sleeve 22 to become disengaged from rod 21. After the measurement is made, wing nut 27 is tightened to lock barrel 14 with respect to frame 12 to thereby prevent the reading of the micrometer from being disturbed by subsequent handling of the instrument.

Figure 2 illustrates the application of the locking device to an inside dimension measuring type 15 micrometer 31 having a knurled barrel 32 which is rotatable with respect to a gauge sleeve 33. In this application of the invention the lower clamp member 18' is of a width sufficient to firmly clamp gauge sleeve 33 without obscuring the calibration 20 markings thereon. In employing the structure of Figure 2 the procedure is the same as with the structure of Figure 1.

The locking device may be readily mounted on a standard micrometer without modifying the 25 structure of the micrometer in any way to receive said locking device. By employing the locking device as above described errors in readings due to accidental rotation of the micrometer parts will be completely avoided.

30 While certain specific micrometer locking structure has been disclosed in the foregoing description, it will be understood that various modifications within the spirit of the invention may occur to those skilled in the art. Therefore it is 35 intended that no limitations be placed on the invention other than as defined by the scope of the appended claims.

What is claimed is:

1. The combination with a micrometer including a gauge sleeve and a barrel rotatable on said sleeve, of a locking device detachably secured to said sleeve and barrel for holding said sleeve and barrel in a fixed relation, said device comprising a clamp member arranged transversely of said 40 gauge sleeve and said barrel and having one end embracing a portion of said barrel, a second clamp member arranged transversely of said sleeve and said barrel and spaced from said first-named clamp member, said second clamp member having 45 one end embracing a portion of said gauge sleeve and secured to the latter portion, a spindle disposed in spaced parallel relation with respect to said gauge sleeve and barrel and rigidly supported in the other end of said second clamping member, a sleeve carried by the other end of said first- 50 55

named clamping member and slidably mounted on said spindle, and means extending through the embracing end of said first-named clamp member for releasing and tightening the clamping pressure of said first-named clamp member with respect to said barrel.

2. The combination with a micrometer including a gauge sleeve and a barrel rotatable on said sleeve, of a locking device detachably secured to said sleeve and barrel for holding said sleeve and barrel in a fixed relation, said device comprising a clamp member arranged transversely of said gauge sleeve and said barrel and having one end embracing a portion of said barrel, a second clamp member arranged transversely of said sleeve and said barrel and spaced from said first-named clamp member, said second clamp member having one end embracing a portion of said gauge sleeve and secured to the latter portion, a spindle disposed in spaced parallel relation with respect to said gauge sleeve and said barrel and having one end rigidly supported in the other end of said second clamp member and having the other end operatively connected to the other end of said first-named clamp member, and means extending through the embracing end of said first-named clamp member for releasing and tightening the clamping pressure of said first-named clamp member with respect to said barrel.

5

to said gauge sleeve and said barrel and having one end rigidly supported in the other end of said second clamp member and having the other end operatively connected to the other end of said first-named clamp member, and means extending through the embracing end of said first-named clamp member for releasing and tightening the clamping pressure of said first-named clamp member with respect to said barrel.

HARRY KERSLAKE.
